CLAIM

The ornamental design for a paint scraper handle, as shown and described.

DESCRIPTION

FIG. 1 is a top plan view of a paint scraper handle showing my new design;
FIG. 2 is a side elevational view thereof, the opposite side being a mirror image thereof;
FIG. 3 is a bottom view thereof;
FIG. 4 is a front end elevational view thereof;
FIG. 5 is a rear end elevational view thereof;
FIG. 6 is a top plan view of another embodiment of a paint scraper handle of my new design employing an elongated arcuate handle portion and an enlarged blade support portion, the surface texturing being only partially shown but extending over substantially the entire surface thereof;
FIG. 7 is a side elevational view of the embodiment of FIG. 6;
FIG. 8 is a top plan view of still another embodiment of a paint scraper handle of my new design with a still longer handle portion, the surface texture being only partially shown but extending over substantially the entire surface thereof; and
FIG. 9 is a side elevational view of the embodiment of FIG. 8.
